UNITED STATES PATENT OFFICE.

MARKS JOSEPH TULLY, OF BROOKLYN, NEW YORK.

SNOW REMOVER.

Application filed June 11, 1920. Serial No. 388,285.

To all whom it may concern:

Be it known that I, MARKS J. TULLY, a citizen of the United States, residing at Brooklyn, in the county of Kings and State 5 of New York, have invented certain new and useful Improvements in Snow Removers, of which the following is a specification.

This invention relates to snow removers and the primary object of the invention is 10 to provide an improved machine for effectively and quickly removing snow and the like from streets and roads with a minimum amount of labor and expense.

Another object of the invention is the provision of an improved means for reducing the snow to a liquid condition so as to permit the same to readily flow through a sewerage system, so that the hauling of the snow to a distant dumping ground is eliminated, there- 20 by permitting the continuous uninterrupted use of the machine for removing the snow from the streets.

A further object of the invention is to provide an improved means for permitting 25 the snow removed from the streets or roads to travel a relatively long distance in the machine so that the snow will be thoroughly acted upon by the means for reducing the same to a liquid state, thereby insuring the 30 effective operation of the machine.

A further object of the invention is the provision of a plurality of high powered torches or flame throwers for reducing the snow to a liquid, the torches or flame throw- 35 ers being so arranged as to act directly on the snow whereby the snow will be quickly and easily melted.

A further object of the invention is the provision of an improved means for spray- 40 ing the snow removed from the streets and roads with water or the like so as to reduce the bulk thereof, a novel pumping system being embodied in the machine for insuring of the effective spraying of the water, means 45 for raising the temperature of the water also being provided, so that the snow will be partially melted or reduced to slush when the water is sprayed on the same.

A further object of the invention is the 50 provision of an improved snow removing machine embodying a plow or scraper, an endless conveyor for receiving the snow from the plow for elevating the same, a series of superposed endless conveyors ar- 55 ranged in rear of and below the first con-

veyor for increasing the travel of the snow through the machine, means for spraying the snow with water as the same is propelled through the machine by the conveyors, and flame throwers or torches for acting di- 60 rectly on the snow as the same falls upon the uppermost conveyor of the superposed conveyors.

A further object of the invention is the provision of a tank arranged below the 65 superposed conveyors for receiving the water from the snow, the water in the tank being treated from the exhaust and cooling systems of the power plants of the machine, means being provided for utilizing the heated water 70 for spraying the snow, and means also being provided for permitting the overflow of the water from the tank to be directed toward the street gutters or sewers.

A still further object of the invention is 75 the provision of means for heating the conveyor utilized for elevating the snow to the series of superposed conveyors so as to prevent the sticking of the snow to the conveyor thereby insuring the effective dump- 80 ing of the snow on the superposed conveyors.

With these and other objects in view, the invention consists in the novel construction, arrangement and formation of parts as will 85 be hereinafter more specifically described, claimed and illustrated in the accompanying drawings, forming a part of this specification, in which drawings:

Figure 1 is a side elevation of the im- 90 proved snow removing machine.

Figure 2 is a central longitudinal vertical section through the machine taken on the line 2-2 of Figure 3.

Figure 3 is a longitudinal horizontal sec- 95 tion through the machine taken on the line 3-3 of Figure 2.

Figure 4 is an enlarged fragmentary horizontal section through the improved ma- 100 chine taken on the line 4-4 of Figure 2 showing a plan view of the superposed conveyors and illustrating the arrangement of the high powered torches or flame throwers in relation thereto.

Figure 5 is a fragmentary detail vertical 105 transverse section through the machine taken on the line 5-5 of Figure 4.

Figure 6 is an enlarged vertical transverse section taken on the line 6-6 of Figure 2, and

Figure 7 is an enlarged fragmentary side elevation of the machine, illustrating the means for permitting the tension of the superimposed conveyor belts to be adjusted.

5 Referring to the drawings in detail, wherein similar reference characters designate corresponding parts throughout the several views, the letter A generally indicates the improved snow removing machine 10 which includes the chassis B, the snow receiving and elevating means C, the snow travel increasing mechanism D, the water spraying device E and the snow melting device F.

15 The frame or chassis B includes a pair of spaced parallel longitudinally extending side channel beams 10 and the cross beams 11. The side beams 10 adjacent to their forward terminals support the semi-elliptical springs 12 which carry the dead axle 13. The terminals of the dead axle 13 have secured thereto in the usual manner the ordinary steering stub axles 14 on which are 20 rotatably mounted the relatively heavy ground steering wheels 15. The wheels 15 may be of any desired construction, provided with solid heavy rubber tires. The steering stub axles 14 are also provided with the usual outwardly extending arms 16 which 25 are connected together by the transversely extending connecting rod 17. This rod 17 has operatively connected thereto the bell crank 18 which is in turn connected to a depending crank 19 by a link 20. The crank 19 is secured to a transversely extending shaft 21 for movement therewith. The shaft 21 is rotatably mounted in suitable 30 bearings 22 bolted or otherwise secured to the side channel beams 10. The terminals of the transverse shaft extend beyond the side beams 10 for a considerable distance, the purpose of which will hereinafter more fully appear and the terminals of the shaft have keyed thereto the crank arms 23 which 35 are in turn pivotally connected to the upwardly extending connecting rods 24. The upper terminals of the connecting rods 24 are pivotally connected to cranks 25 which are secured to a second transversely extending shaft 26, which is supported by the housing for the endless conveying mechanism C which will be hereinafter described. The shaft 26 extends transversely of the machine and is positioned directly below the operator's cab 27 and this shaft has keyed or otherwise secured thereto a suitable worm wheel 28, which meshes with a worm 29 carried by the steering post 30. The steering post 30 is provided with the usual steering wheel 31. Thus it can be seen that upon movement of the steering wheel, the stub shafts 14 will be turned.

40 A power plant 32 is arranged intermediate the ends of the frame or chassis B for operating the various conveyors, spray-

ing mechanism and the like, while a second power plant 33 is provided for driving the machine. The power plant 33 is located adjacent to the rear end of the chassis or frame B and is secured thereto in any preferred manner. These power plants 32 and 33 may be of any preferred style or make and as shown these power plants are of the internal combustion engine type. The crank shaft 34 of the internal combustion engines 75 33 is extended forwardly and provided with a worm 35, which meshes with a worm wheel 36 keyed to or otherwise secured to a transversely extending shaft 37. The shaft 37 has keyed thereto a relatively small sprocket wheel 38 around which is trained a sprocket chain 39. The sprocket chain 39 constitutes the means for operating the drive mechanism 40 of the snow remover. A suitable 80 brake mechanism 41 is carried by the shaft 37 for decreasing or stopping the rotation of the shaft when desired. This brake mechanism is operated in any preferred manner from the driver's cab 27.

85 The driving mechanism 40 of the snow remover includes a pair of spaced longitudinally extending bars 42 which have mounted on their upper surface spaced bearings 43 in which are rotatably mounted a pair of spaced transversely extending shafts 44. These shafts 44 have keyed to the terminals thereof the relatively broad sprocket wheels 45 and a traction belt 46 is trained around the wheels. The traction belt 46 has its outer surface provided 90 with a plurality of transversely extending cleats 47, which form means for permitting a firm grip to be obtained on the ground. While the driving mechanism 40 for the snow remover has been shown to be of the caterpillar type, it is to be understood that ordinary drive wheels may be provided if so desired. The axle 44 which supports the forward relatively large sprocket wheels 45 has keyed thereto a relatively large drive 95 sprocket wheel 48 and this sprocket wheel has trained around the same the drive sprocket chain 39. Thus it can be seen that an effective means has been provided for operating the driving mechanism from the internal combustion engine 33. It is also to be understood that suitable clutches and control devices for the internal combustion engine 33 are provided and these means are to be operated from the cab 27 in the usual or any preferred manner. The internal combustion engine 33 is provided with a suitable water cooling system which includes a radiator 49 which is secured to the rear end of the channel beams 10. The radiator 49 is of any preferred construction and has connected thereto in the usual manner the return and supply water pipes 50. An exhaust pipe 51 is also provided for the 100 exhaust manifold of the engine 33 and this 105 110 115 120 125 130 135

pipe is disposed in such a manner that the waste heat of the engine will be utilized and this means for utilizing the heat will be hereinafter described.

5 The longitudinally extending side bars 42 and the driving mechanism 40 supports intermediate their ends brackets 52, and the terminals of these brackets carry suitable rollers 53 and 54 which are adapted to engage respectively the upper and lower runs 10 of the traction belt 46 so as to prevent any slack in the belt intermediate the sprocket wheels 45. The snow receiving and elevating mechanism C is arranged at the forward 15 end of the snow removing machine and the same projects forwardly of the frame or chassis B and below the driver's cab 27. This mechanism includes a frame 55 which is connected to the chassis or frame B in any preferred manner. The frame 55 includes upper and lower inclined walls 56 and 57 and connecting side walls 58. The cab 27 is located directly on the upper wall 56 of the frame which forms a convenient 20 means for supporting the same. The forward and rear ends of the side walls 58 rotatably support transversely extending shafts 59 and 60 and these shafts have keyed or otherwise secured thereto at spaced points 25 sprocket wheels 61 which have trained around the same drive sprocket chains 62. The drive sprocket chains 62 are connected by transversely extending flights 63 and these flights and sprocket chains constitute 30 the endless conveyor for engaging the snow in the machine. The transversely extending flights 63 are of substantially hollow V-shaped construction in cross section and are secured to the sprocket chain in any preferred manner. The flights are preferably 35 of hollow configuration for a purpose which will be hereinafter more fully described. The side walls 58 of the frame 55 also support intermediate their ends a table 64 which is arranged in spaced parallel relation 40 to the upper and lower walls 56 and 57. This table forms a means for supporting the upper run of the sprocket chains 62 and forms a support for the snow to be elevated. This table is provided with a plurality 45 of perforations so as to permit any snow which might be reduced to a liquid state to seep therethrough. This conveying mechanism extends slightly beyond the lower wall 57 so that the snow being elevated will be propelled beyond the same. The means for introducing the snow on the conveying mechanism and for scraping the snow from the street or roads includes a 50 shovel or scraper plow 66. The shovel or scraper plow 66 includes the side walls 67 and the lower wall 68. The rear end of the lower wall is provided with an inwardly extending arcuate extension 69 which is adapted 55 to engage the forward curved end of the bottom wall 57. The walls 67 of the shovel or plow are pivoted in any preferred manner to the side walls 58 of the frame 55 so as to permit the plow or shovel to be raised or lowered. The lower end of the bottom wall 68 of the plow or shovel is adapted to scrape the snow or the like from the surface of the street or road over which the snow removing machine is being propelled, and to protect the forward edge of the bottom wall, a plurality of guide fingers 70 are secured to the forward edge thereof. The shovel or scraping plow is swung from the driver's cab in any preferred manner, and as shown 60 rods 71 are connected to the upper edge of the side walls and these rods extend to suitable operating levers or foot pedals arranged in the operator's cab adjacent to the steering post 30.

The side bars 42 of the driving mechanism 40 of the chassis frame B is connected in any preferred manner to the relatively long longitudinally extending side members 72 and the forward ends of these members 72 are connected by partial elliptical leaf springs 73 with the side channel beam 10 by any preferred type of shackle 74. The rear ends of the side members 72 are connected by means of a transversely extending semi-elliptical spring 75 to the rear ends of the side channel beams 10. The means employed for connecting the driving mechanism 40 to the frame reduces the transmission of shocks to the machine incident to the travel thereof over roadways. The side beams 10 have secured thereto at spaced intervals the upstanding vertically disposed channel beams 76 which form means for supporting and bracing the housing 77 for the snow travel increasing mechanism D which 100 will be now described. The housing 77 for the snow travel increasing mechanism D includes side walls 79 which may be formed a continuation of the side walls 58 of the frame 55. The side walls 79 have also secured thereto the front and rear walls 80 and 81. A depending tank 82 is formed on the housing and is adapted to receive the liquid resulting from the snow after the same has been melted. The snow travel increasing mechanism D includes a plurality of superposed horizontally disposed conveyors 83, 84 and 85. These conveyors are all constructed substantially alike, and a description of one will suffice for all. As shown, 105 the conveyors each include pairs of spaced sprocket chains 86 which are trained around pairs of spaced sprocket wheels 87 which are keyed or otherwise secured to pairs of spaced shafts 88, which are rotatably carried by the side walls 79 of the housing. These chains are connected by transversely extending hollow V-shaped flights or blades 89 which are adapted to engage the snow 110 and propel the same through the machine. 115

130

The upper runs of the conveyors 83, 84 and 85 are supported by horizontally disposed perforated supporting tables 90 which are also carried by the side walls 79 of the housing. The conveyors are also separated by transversely extending partition plates or platforms 91 which form means for receiving the snow as the same drop off of the tables 90. It is to be understood that the conveyors 10 may be positioned at various distances apart so that as the snow decreases in bulk, the conveyors will be able to effectively engage and propel the same through the machine. Each of the transversely extending 15 partition plates or platforms 91 extend forwardly from the wall 81 of the housing 77 and terminate short of the front wall 80. The inner surfaces of the front wall and the rear wall 80 and 81 are suitably curved 20 to conform to the arc in which the flights or blades 89 swing as the same ride over the sprocket wheels 87. Thus it can be seen that as the snow is brought up the inclined endless conveyor formed by the sprocket 25 chain 62 and 63, the same will be dropped on the uppermost horizontally disposed conveyor 83 which will carry the snow rearwardly and deposit the same on the uppermost partition plate or platform 91. The lower run of the uppermost conveyor 83 will then propel the snow off of the platform where the same will drop on the intermediate conveyor 84 which will again carry the snow rearwardly and deposit the same on the intermediate platform or partition 91. The lower run of the intermediate conveyor 84 will then propel the snow forwardly and off of the intermediate platform and on the lowermost conveyor 85. The lowermost conveyor 30 85 will again carry the snow rearwardly and deposit the snow on the lowermost platform or partition plate 91, after which the lower run of the lowermost conveyor will propel the same into the tank 82 provided for that purpose. Thus it can be 35 seen that the snow is given a tortuous passage through the machine and is acted on by means for reducing the same to a liquid state. The tank 82 rests upon the upper 40 surface of the side beams 10 and an overflow pipe 95 is positioned therein. The upper end of the overflow pipe is provided with an inverted goose neck 96 and when the water reaches a predetermined height in the tank 45 the same will ride into the overflow pipe. The lower end of the overflow pipe extends outwardly of and below the tank and terminates adjacent to one of the side beams 10. The outer end of this pipe is adapted to 50 have a hose or the like connected thereto so that the water from the tank will be directed toward a gutter or sewer.

The water spraying device E provided for 55 decreasing the bulk of the snow and for partially melting the same includes a storage

tank 97 which is secured in place by suitable brackets 98. The water is stored in the tank 97 by means of a suitable water pump 99 which is secured to the frame B in any preferred manner in advance of the internal combustion engine 32, which is connected thereto in any preferred manner for operating the same. The inlet pipe 100 of the water pump 99 extends rearwardly to the tank 82 and is provided with a suction nipple 101. Thus it can be seen that the water for the pump is taken from the tank 82. The outlet pipe 102 of the water pump 99 is connected to the storage tank 97. This tank 97 has connection with a cross pipe 103, one terminal of which extends upwardly as at 104 and communicates with a substantially U-shaped pipe 105, the legs of which extend over the endless conveyor formed by the chains 62 and the flights or blades 63. Thus 60 it can be seen that as the snow reaches the upper end of the conveyor the snow is thoroughly sprayed with the water from the tank 82, which effectively reduced the bulk of the snow and reduces the same to a slush. 65 The opposite end of the cross pipe 103 has connected thereto a substantially U-shaped pipe 106 the legs of which extend into the housing 77 and these legs have connected thereto for communication therewith the 70 longitudinally extending pipes 107. The pipes 107 are disposed above the upper and intermediate partition plates or platforms 91 and it will be seen that as the snow or slush falls upon the plates or partition the 75 snow is thoroughly sprayed with the water. Means is provided for heating the water in the tank 82 so that the temperature of the water will be raised when the same is sprayed upon the snow so that an effective 80 means will be provided for reducing the snow to a slush. The means provided for heating the water consists in extending the exhaust pipe 51 of the internal combustion motor 33 into the tank 82 and the terminal 85 of the exhaust pipe 51 is connected to a substantially U-shaped pipe 109. The legs of the U-shaped pipe 109 are bent inwardly toward each other as at 110 and then upwardly and inwardly in spaced parallel relation to 90 the legs of the U-shaped pipe. Thus it can be seen that a coil like body is provided for the exhaust pipe, so that a relatively large amount of heat radiating surface is provided. The cooling system for the internal 95 combustion engine 32 also obtains its supply of water from the tank 82 and the return pipe 111 thereof empties into the tank and it can be seen that this will also tend to raise the temperature of the water. The inlet 100 pipe 112 extends into the bottom of the tank and is provided with a suitable perforated suction nozzle which prevents the entrance of dirt and the like into the pipe.

The endless conveyor formed by the chain 105

62 and the flights or blades 63 and the conveyors 83, 84 and 85 are driven by the internal combustion engine 32. The crank shaft 113 of the internal combustion engine 32 is 5 provided with a worm 114, which meshes with a suitable worm wheel keyed or otherwise secured to a transversely extending shaft 115 rotatably mounted in suitable bearings 116 bolted to the longitudinally extending side beam 10. This shaft 115 is operatively connected to a second transversely extending shaft 117, by means of a suitable sprocket chain and wheel connection 118. The shaft 117 extends transversely across 10 the frame B and has the terminals journaled in the forward pair of vertically disposed channel beams 76. The shaft 117 is operatively connected to the longitudinally extending shaft 119, by means of a worm 120 which meshes with a worm wheel 120' carried by the shaft 119. The shaft 119 is utilized for driving the water pump 99. One of the vertically disposed channel beams 76 is provided with suitable bearings for 15 supporting a vertically disposed shaft 121. The vertically disposed shaft 121 is connected by means of bevelled gears 122 with the transversely extending shaft 117. The shaft 121 is utilized for driving the superposed 20 conveyors 83, 84 and 85 and the forward shafts of these conveyors have their terminals extended through the channel beam 76 and has keyed to the outer end thereof the bevelled gears 123. The bevelled gears 123 mesh with suitable bevelled gears 124 which are keyed to the vertically disposed shaft 121. Thus it can be seen that the superposed conveyors are effectively operated. The conveyors 83 and 84 and 85 have the 25 tables 90 thereof resting upon suitable channel beams 126 which are also provided bracing the housings 79. Angle irons 127 are also secured to the side walls 79 of the housing and form supports or guides for the blades or flights 89 and the terminals of the blades rest upon the angle irons. Means is also provided for tensioning the chains 30 of the conveyors 83, 84 and 85. This means for tensioning the chains consists of providing bearings 129 which receive the rearmost shafts 88 of the conveyor. The sides 79 of the housing 77 for the conveyor and the rearmost pair of channel beams 76 are provided with aligned slots 130 through 35 which the shafts 88 extend. The bearings 129 have the terminals thereof provided with openings for the reception of screws 131, which are mounted in suitable brackets 132 carried by the channel beams 76. The screws 131 have fitted thereon nuts 133 and 40 134. The nuts 133 engage against the outer side of the brackets 132 while the nuts 134 engage the opposite faces of the bearings 129. It can be seen that by adjusting the nuts 134 the bearings can be slid longitudinally 45 of the housing and thus permit the shafts 88 to be shifted and thus permit of the tensioning of the conveyor.

The uppermost shaft 88 has one terminal thereof provided with a sprocket wheel 135 and this sprocket wheel is in alignment with a sprocket wheel 136 which is keyed or otherwise secured to the rearmost shaft 60 of the endless inclined conveyor formed by the sprocket chain 62 and the flights 63. The sprocket wheels 135 and 136 have trained around the same a drive sprocket chain 137 and thus it can be seen that when the shaft 121 is rotated by the internal combustion engine 32 the inclined conveyor formed by the chains 62 and the flights 63 and the superposed conveyors 83, 84 and 85, will be operated. The supporting table 64 for the chains 62 has its terminals secured to longitudinally extending inclined beams 138, which also provide means for effectively bracing the table throughout its length. The table is further braced by means of longitudinally extending beams 139, which are arranged in spaced parallel relation to the side channel beams 138 and these beams 139 are supported by suitable cross braces 140. The plates 63 are also held in their correct position during their passage over the table by means of angle irons 141, which are also secured to the side walls 58 of the frame 55. The frame is also braced throughout its length by frames 142, which extend entirely around the frame. The internal combustion engines 32 and 33 are cranked in any preferred manner and as shown a hand crank 144 is provided for the forward engine 32. The frame B has secured thereto in any preferred manner the supply tank 145 which is adapted to receive the fuel for the engines 32 and 33 and the same are fed from the tank 145 in any preferred manner.

The exhaust pipe 146 of the internal combustion engine 32 is extended into the frame 55 for the forward end of the conveyor as 55 at 147 and the exhaust gases escaping into the frame effectively heat the snow so as to permit the temperature thereof to be raised. The exhaust pipe terminates in the casing directly between the upper and lower runs 115 of the conveyor and as the flights 63 are of hollow formation the exhaust gases will have a tendency to flow into the same and thereby heat the sides thereof. This will effectively prevent the sticking of the snow to 120 the blades and facilitate the dumping of the snow on the superposed conveyor. The means F provided for melting the snow includes a battery of high power torches or flame throwers 148 and these torches or 125 flame throwers are arranged longitudinally and transversely of the housing 77. As shown a plurality of torches 149 are carried by the side walls 79 of the housing 77 and these torches are located directly above 130

the uppermost conveyor 83 and are adapted to project the flame directly on or into the snow as the same rides by on the conveyor. The rear wall 81 also carries a plurality of 5 torches or flame ejectors 150 and it can be seen that as the snow is brought rearwardly toward the rear wall 81, the snow will be acted directly upon by the torches. The batteries of the torches or flame projectors 148 10 are connected in series by means of a feed pipe 151 which communicates with the supply fuel tank 152 which is arranged at the rear end of the frame or chassis B. A suitable supplemental supporting frame 153 is 15 built on the rear end of the chassis for supporting the fuel tank. A hand operated valve 154 is interposed in the fuel supply pipe 151 so that the fuel for the torches or flame projectors may be cut off or controlled. 20 Also independent hand operated valves 155 are provided for each one of the flame projectors so that the same may be individually controlled. The tank 152 may contain any suitable or preferred type of fuel for the 25 torches or flame projectors, such as kerosene, gasoline or the like. The fuel is forced from the tank 152 into the feed pipe 151 by means of air pressure and this air pressure is maintained by a relatively small air 30 pump 156 which is actuated from the crank shaft of the internal combustion engine 33. To prevent the pressure in the tank from rising beyond a predetermined degree, a suitable automatic air-escape valve 157 is 35 provided. This valve permits the air to escape from the tank after a predetermined pressure has been reached.

In operation of the improved snow remover, the machine is driven to the place 40 where the snow is to be collected. The scraping plow or shovel 66 is then lowered until the projecting prongs or teeth 70 are in engagement with the ground. The machine is then started and it will be seen that the plow 45 66 will effectively collect the snow and direct the same on the endless inclined conveyor formed by the chains 62 and flights 63. The flights 63 will carry the snow up the inclined table 64 and as the snow reaches 50 the upper end of the same, the snow will be thoroughly sprayed and washed by the water from the U-shaped pipe 105. This will effectively decrease the bulk of the snow and have a tendency to reduce the same to a 55 slush. The flights 63 are heated by means of the exhaust gas from the engine 32 which will prevent the sticking of the snow on the blades or flights. The snow is then dropped on the uppermost conveyor 83 of the super- 60 posed conveyor and as the snow is directed rearwardly by the conveyor, the snow will be acted upon directly by the flame throwers or projectors which will reduce the same to a liquid or semi-liquid condition. The snow 65 is then deposited up on the uppermost par-

tition plate or platform 91 where the same is again acted upon by water from the pipes 107 which tends to reduce the snow to a liquid state. The snow is scraped off of the uppermost partition plate or platform 91 70 by the flights or blades 89 of the lower run of the conveyor. As the snow is scraped off of the uppermost platform or partition plate 91 the same falls on the intermediate conveyor 84 and is directed toward the rear end 75 of the machine. When the snow reaches the rear end of the machine the same is deposited upon the intermediate partition plate or platform 91 where it is again acted upon by water sprayed from the pipes 107. The 80 flights carried by the lower run of the intermediate conveyor 84 will propel the snow or the like off of the plate and direct the same on the lowermost conveyor 85. The snow or slush is again directed toward the 85 rear end of the machine where it falls on the lowermost platform or partition plate 91 when it is again scraped toward the front of the machine. When the snow is pushed to the forward end of the lowermost platform the same is dropped into the tank 82 where the same can be directed toward a gutter or sewer. The water in the tank 82 has its temperature effectively raised by the 90 exhaust gases and other means heretofore described so that as the water leaves the tank the same will be prevented from freezing. In starting out with the improved machine the tank 82 may be partially filled with water if desired or necessary. 95

From the foregoing description it can be seen that an improved snow removing machine has been provided, which will effectively scrape all snow from streets and roadways and reduce the same to a liquid condition whereby the same can readily flow off through the sewerage system of the city. 100

Changes in details may be made without departing from the spirit or scope of this invention; but,

I claim:

1. In a snow removing machine, a plow, an endless inclined conveyor arranged in rear of the plow, superposed conveyors arranged in rear of the first mentioned conveyor, means for spraying the snow with water to reduce the same to a slush, and means for acting on the snow in rear of the water spraying device. 115

2. In a snow removing machine, an endless inclined conveyor, a scraper blade hingedly secured in front of said conveyor, a plurality of superposed horizontally disposed endless conveyors arranged in rear of and below the inclined conveyor, partition plates arranged intermediate the superposed conveyors, said plates terminating short of the forward ends of the conveyor, means for spraying water on the snow as the same is being conveyed by the conveyor, 120

125

130

and flame projectors or torches arranged to act directly upon the snow as the same leaves the inclined conveyor.

3. In a snow removing machine, means for collecting and introducing snow into the machine, a plurality of superposed independent conveyor belts arranged in the machine to receive the snow, a plurality of flame projectors arranged around the uppermost conveyor of the superposed conveyors, and water spraying means disposed around the other conveyors.

4. In a snow removing machine, a chassis including steering wheels, driving wheels, means for propelling the driving wheels, a supplemental power plant, a scraper blade hingedly carried by the forward end of the chassis, means for raising and lowering the scraper blade, an inclined conveyor belt, a tank arranged below the inner end of the conveyor belt, a plurality of superposed horizontally arranged conveyor belts arranged intermediate the tank and the inclined conveyor belt, means for operating said conveyor belts from the supplemental power plant, a water pump, means for operating the water pump from the power plant, and means for spraying water from said pump, on the snow disposed on said conveyor belts.

5. In a snow removing machine, a frame, a scraper blade carried by the frame, an endless inclined conveyor arranged in rear of the scraper blade, a plurality of superposed conveyor belts arranged in rear of and below the inclined conveyor, partition plates arranged intermediate the superposed conveyors and terminating short of the conveyors, perforated supporting plates arranged to engage the upper runs of the conveyors, a feeding pipe arranged below the conveyors, a water supply system, means for spraying water on the inclined conveyor belt, means for spraying water on the superposed conveyor belts arranged below the uppermost belt thereof, and batteries of flame projectors and torches formed around the uppermost conveyor of the superposed conveyors.

6. In a snow removing machine, a frame, steering wheels carried by the frame, a drive mechanism carried by the frame, a power plant, means for operatively connecting the power plant with the drive mechanism, a supplemental power plant, an inclined endless conveyor carried by the forward end of the frame, a scraper blade carried by the forward end of the frame and arranged in front of the endless conveyor, a plurality of superposed conveyors arranged in rear of the inclined conveyor, a tank arranged below the superposed conveyors, means for operating the conveyors from the supplemental power plant, a water pump, means for operating the water pump from the sup-

plemental power plant, an inlet pipe for the water pump leading from the tank, a supply tank, the outlet pipe for the pump being connected to the supply tank, and spraying pipes leading from said supply tank and arranged above certain of the conveyor belts.

7. In a snow removing machine, a frame, steering wheels carried by the frame, traction means carried by the frame, a power plant, means operatively connecting the power plant with the traction means, a supplemental power plant, an inclined conveyor carried by the forward end of the machine, a scraper blade carried by the forward end of the inclined conveyor, a plurality of superposed conveyors arranged in rear of and below the endless conveyor, a tank arranged below the superposed conveyors, a supplemental power plant, means operatively connecting the supplemental power plant with the conveyors, means for leading the cooling water for the jackets of the supplemental power plant into the tank, means for directing the exhaust gases from the first mentioned power plant to the tank, means for directing the overflow of the tank laterally of the machine, a plurality of torches, a fuel supply tank therefor, a fuel pipe leading from said fuel tank to the torches, means for controlling the flow of fuel therethrough, means for controlling the flow of fuel to each torch, and means operated from the first mentioned power plant for maintaining a predetermined pressure in said fuel tank.

8. In a snow remover, a frame, a traction device carried by the frame, a power plant, means for operating the traction device from the power plant, an inclined housing carried by the forward end of the frame, a housing carried by the rear end of the frame and communicating with the inclined housing, an endless inclined conveyor belt arranged in the inclined housing, an inclined supporting plate arranged in the inclined housing for engaging the upper run of the endless conveyor belt, a hinged scraper carried by the forward end of the inclined housing, a plurality of superposed horizontally disposed conveyor belts arranged in the second mentioned housing, a tank arranged in and forming a part of the second mentioned housing, a supplemental power plant, means for operating said conveyor belts from said power plant, a plurality of perforated supporting plates arranged in said second housing and adapted for supporting the upper run of the horizontally disposed superposed conveyor belts, partition plates arranged intermediate the superposed conveyor belts and adapted to be engaged by the lower runs of the superposed conveyor belt, means for spraying water on the first mentioned inclined conveyor belt adjacent

to the rear end thereof, flame projectors arranged around the uppermost conveyor belt of the superposed conveyor belts, and water spraying devices arranged below the uppermost and intermediate conveyors of the superposed conveyor belts.

9. In a snow removing machine, means for collecting and elevating the snow, means for

receiving the snow from the collecting and elevating means, flame projectors surrounding said snow receiving means for acting directly upon the snow, and means for spraying the snow with warm water after the same has been acted upon by the flame projectors.
